Primary Examiner — Cynthia Ramirez(74) *Attorney, Agent, or Firm* — Carlson, Gaskey & Olds, P.C.(57) **CLAIM**

The ornamental design for a waste container, as shown and described.

DESCRIPTION

FIG. 1 is a perspective view of a waste container, showing my new design.

FIG. 2 is a first side view of the waste container.

FIG. 3 is a front view of the waste container.

FIG. 4 is a second side view of the waste container.

FIG. 5 is a top view of the waste container.

FIG. 6 is a bottom view of the waste container; and,

FIG. 7 is a rear view of the waste container.

The broken lines in the figures are to show portions of the waste container and form no part of the claimed design.

1 Claim, 7 Drawing Sheets(56)
